220,090

EXTRUDED BEAM FOR SWIMMING POOLS

William A. van den Broek, Doylestown, Pa., assignor to Sylvan Pools, Inc., Doylestown, Pa.

Filed Oct. 28, 1969, Ser. No. 19,762

Term of patent 14 years

Int. Cl. D25—99

U.S. Cl. D13—1

The sole figure is a perspective view of a beam embodying my invention.

I claim:

The ornamental design for an extruded beam for swimming pools, as shown and described.

References Cited

UNITED STATES PATENTS

D. 162,843	4/1951	Klein	-----	D13—6
D. 216,956	3/1970	Dallaire	-----	D13—6

A. HUGO WORD, Primary Examiner